UNITED STATES PATENT OFFICE.

LESTER L. JONES, OF NEW YORK, N. Y., ASSIGNOR TO POWERFONE COMPANY, OF NEW YORK, N. Y., A PARTNERSHIP COMPOSED OF WILLIAM DUBILIER, LESTER L. JONES, AND ALLEN D. CARDWELL.

TELEPHONE RECEIVER.

Application filed May 2, 1922. Serial No. 557,838.

The invention relates to an instrument for transforming electrical impulses into sound waves, such as telephone receivers and the like, and the features of the invention, although of quite general application, are particularly useful in connection with receivers operating with substantial amounts of power, and adapted to produce sound waves of large volume.

One object of the invention is to provide a receiver of the above type wherein the magnetic circuits are so related as to be highly sensitive to changes in electrical impulses impressed thereon, whereby the sound wave generating diaphragm which is operated by changes in the magnetic circuit, may be caused to produce distinctly and sharply the sound waves corresponding to different electrical impulses.

Another object is to construct the instrument so as to permit the armature which operates the sound-producing diaphragm, to be intimately related to the pole pieces of the magnets with which it cooperates, and yet without danger that the slight spacing between such armature and the pole pieces will be likely to cause sticking of the armature between or against the same. It is also desired to employ a magnet structure which will decrease the length of the armature flux path by permitting the pole pieces which influence such armature, to be set very close together.

The invention also aims to enable the use in receivers of the above character of diaphragms which are exceedingly thin, flexible and of light weight, and therefore capable of responding sensitively to changes in the magnetic field, but under such conditions that a large gap need not be employed in connection with the diaphragm to insure that the impulses are transmitted to a relatively large area thereof, or to prevent sticking against the pole pieces.

Another object is to segregate, so to speak, the variable magnetic circuit of the receiver from the constant magnetic circuit thereof so as to enable each of such circuits to react efficiently upon the diaphragm, and eliminate losses which might occur due to interaction between such circuits.

Another object is to provide a receiver wherein a sound-producing diaphragm and an armature for actuating same are so com-

bined and related to the magnetic circuits of the receiver that the magnetic forces will produce a maximum effect upon the diaphragm.

The invention also aims to permit energy transfers from the sound-producing diaphragm to the surrounding air without the generation of objectionable resonance tones, by employing a diaphragm which communicates with the outer air through an opening of relatively large area.

Further objects and advantages of the invention will be in part obvious and in part specifically pointed out in the description hereinafter contained, which, taken in connection with the accompanying drawings, discloses certain preferred embodiments thereof; such embodiments, however, are to be considered merely as illustrative of its principle. In the drawings:

Fig. 1 is a front elevation of the essential parts of a telephone receiver made in accordance with the invention.

Fig. 2 is a plan view of the structure shown in Fig. 1.

Fig. 3 is a section on line 3—3 of Fig. 2 looking in the direction of the arrows.

Fig. 4 is a front elevation showing a casting operatively related to the parts of the receiver which appear in Figs. 1 to 3.

Fig. 5 is a diagrammatic view illustrating a modification of certain features of the invention.

Referring to the drawings, a telephone receiver is illustrated having a permanent magnetic circuit embodying a magnet 1, which may be of any convenient shape, and which in the present instance is shown as of the horseshoe type, having poles 2 and 3, between which are located pole pieces 4 and 5 which will be more fully described hereinafter. In the illustrated embodiment of the invention the magneto motive force of the above-mentioned magnetic circuit is obtained entirely from the permanent magnet 1, which is preferably of relatively large power, whereby the flux emanating therefrom constitutes a relatively large fraction of the total flux which influences the sound-producing diaphragm of the receiver.

In connection with the above-mentioned magnetic circuit there is employed a variable magnetic circuit, which in the present form is made up of leg 6 integral with the pole

piece 5 previously described, and extending across the inner face of pole piece 3 of the permanent magnet, and a further magnetic member of angle shape having a pole piece 5 interposed between the pole pieces 4 and 5 previously mentioned, and a leg 8 extending toward leg 6 previously described.

Variable magneto motive force for said last-mentioned magnetic circuit is obtained 10 by means of a coil 9, which in the present instance surrounds a part pole piece 7.

The sound-producing diaphragm is influenced by means of the flux passing between the pole pieces 5 and 7 via the armature 15 through gaps 10, which are common to the permanent or constant-magnetic circuit, and the variable or branch magnetic circuit which is affected by coil 9. This last-mentioned circuit is later referred to as being in 20 parallel with the permanent or constant magnetic circuit, since permanent flux passes, for example, from pole 2 to pole pieces 4 and 7, and across gap 10 to pole piece 5 and pole 3; it should be noted however that the above arrangement also provides a parallel path for the permanent flux 25 which includes elements 2, 4, 7, 8, 6 and 3 and in a parallel path 7, 8—14, 6, 3.

The magnetic system is so arranged as to 30 maintain substantially constant flux in the magnetic circuit, comprising magnet 1, by including a portion of relatively high reluctance in such circuit, which is in series with pole pieces 5 and 7, and the variable 35 magnetic circuit. As shown in Fig. 1, this portion of high reluctance takes the form of a flux-limiting gap 11 interposed between the pole pieces 4 and 5, which gap limits the total amount of flux passing through the 40 permanent magnetic circuit, and fixes the amount of permanent flux passing across the gap 11, regardless of the changes in the variable magnetic circuit which are produced by coil 9.

45 The provision of a high reluctance portion such as gap 11, in the permanent magnetic circuit, opposes any tendency of the flux from the variable magnetic circuit passing through permanent magnet 1, whereby hysteresis and eddy current losses are avoided in the magnet 1, due either to changes in the permanent flux, or the passage of flux therethrough which is generated by coil 9. Thus with circuits of the above 50 nature the pole pieces 5 and 7 and the elements 6 and 8 may be laminated as indicated in Fig. 2, to cut down the losses in the variable magnetic circuit, but the permanent magnetic circuit, which may not be very 55 readily constructed of laminated pieces, will not cause increased losses due to flux variations therein.

Fig. 5 illustrates a modification of this idea, wherein a permanent magnet 1^a is provided with poles 2^a and 3^a, and pole pieces

7^a and 4^a carrying flux-varying coils 9^a and 9^b, which are mounted on the poles 2^a and 3^a respectively, together with legs 8^a and 6^a extending between the poles 2^a and 3^a to provide a shunt path for the variable magnetic flux produced by coils 9^a and 9^b. In this instance the flux passing around through magnet 1^a is limited by means of short circuited loops 12 and 13 of copper or the like enclosing the poles 2^a and 3^a, which members 12 and 13 oppose the passage of variable flux around through the magnet 1.

Referring again to the embodiment of the invention illustrated in Figs. 1 to 3, the variable magnetic circuit is also provided with a portion of high reluctance, such as air gap 14, in the present instance interposed between the legs 6 and 8 previously described, to balance the flux passing through the permanent magnetic circuit, and to insure that a proper proportion thereof will pass across the gap 10 between pole pieces 7 and 5.

It is obvious that the short-circuiting means such as the loops 12 and 13 of copper or the like, shown in Figure 5, may be applied to the embodiment of the invention illustrated in Figures 1 to 3. Here the short-circuiting loops may consist of copper or the like arranged in the position shown in Figures 1 and 2 and indicated by the numerals 12^a.

It will be noted that coil 9, being located in the shunt part of the variable circuit, has no effect upon the permanent flux which passes across the gap 11, but serves to divert a variable portion of the permanent flux through gaps 10 and furthermore this coil being located in the shunt part of such circuit does not require a spacing between the pole pieces 5 and 7 conforming to the dimensions of the coil. In other words the pole pieces 5 and 7 may be set very close together, so as to reduce the reluctance of armature 15 and its weight, as contrasted to a structure, for example, as illustrated in Fig. 5, where the pole pieces 4^a and 7^a are spaced a distance equal to or greater than the diameter of one of coils 9^a or 9^b.

The disposition of the coil 9^a in the shunt part of the variable magnetic circuit also avoids the necessity of employing two coils of this nature, as has often been done.

In the illustrated embodiment of the invention a separate armature 15 is disposed adjacent the pole pieces 5 and 7 and connected to the diaphragm 16 (Fig. 1) to move the latter in accordance with the variations in flux between pole pieces 5 and 7. The armature 15 is enabled to be spaced very slightly from the pole pieces, as hereinafter described in greater detail, and as such pole pieces are set very close together, the length and reluctance of the armature are very small. For example, the armature air gap may be ten thousandths of an inch, and the

distance between adjacent surfaces of the pole pieces 5 and 7 need not be greater than sixty thousandths of an inch with the armature overlapping each pole piece by .050 inch, the total length (in direction of flux) of the armature is only 0.130 inch. It is also preferred to employ an armature of dimensions so related to the magnetic forces acting thereon that the ratio of magnetic 10 pull to the weight of the armature may be substantially at a maximum. The condition is substantially satisfied by the equation $L = \sqrt{8TMG}$, where L is the dimension of the armature in the direction of the flux, T the thickness of the armature, M the permeability of the armature, and G the normal 15 distance between the armature and the pole pieces. Thus the magnetic flux passing through the armature will be relatively 20 large, while the mass or weight of the armature is relatively small, resulting in the application of efficient forces to the diaphragm 16 to influence the same.

The pole pieces 5 and 7 are also preferably so shaped and related to the remainder of the magnetic structure as to concentrate the flux between the pole pieces, in the region of the armature 15. As shown, the surface 5^a of the pole piece 5, which opposes pole piece 25 7, is beveled back, or tapered toward the armature, while the surface 7^a of the pole piece 7 is also cut away to direct the major portion of the flux in pole piece 7, through the opposite portion of such pole piece which 30 is adjacent the armature. As appears in Fig. 1, the cross sectional area of the pole pieces 5 and 7 furthermore preferably is made relatively small, with respect to the 35 remaining magnetic parts of the magnetic 40 circuits including such pole pieces, whereby the flux density in the pole pieces is relatively greater or more concentrated.

It is also preferred to employ a diaphragm 16, the effective weight in motion of which is 45 substantially equal to the weight of the armature. If a heavier diaphragm is employed the motion imparted thereto when the armature 15 is actuated by the magnetic 50 forces, is relatively small, while if the diaphragm is too light, the forces of the magnetic pull are transmitted only to a relatively small fraction of the area thereof.

In order to permit the use of a very small air gap between the armature 15 and the pole 55 pieces 5 and 7, without danger of the armature snapping over against or sticking to the pole pieces, it is also preferred to apply external forces to the armature 15, urging the same in the direction of the magnetic 60 pull. In the present instance, the armature is connected to diaphragm 16 at its intermediate portion, and suitable means such as metallic threads 16^a (Figs. 2 and 3) are affixed to the ends of the armature and placed 65 under tension as by suitable binding screws

17. When the screws 17 are tightened up to apply tension to the threads 16^a, the armature 15 is pulled toward the pole pieces, and the diaphragm 16 is flexed as indicated in Fig. 1. Threads 16^a lie in the plane of the 70 gap when the armature touches the poles so that they no longer urge armature towards pole. The combination of this rapidly disappearing gap closing force with the diaphragm reaction, presents a rapidly increasing 75 resistance to further flexure, thus counteracting the tendency of the increased magnetic pull as the armature approaches the pole pieces, to stick the armature against the same. Preferably the forces exerted by the 80 threads 16^a upon the armature when the armature is in its operating position are greater than the maximum magnetic pull which may be imposed upon the same for any 85 armature gap length, to insure the maintenance of the air gap between the armature and the pole pieces under all conditions.

Where an armature spaced from both pole pieces is employed, as in the case of the illustrated embodiment, it is preferred to so 90 connect the armature to the diaphragm 16 as to permit equalization of forces applied thereto by the threads or members 16^a. In the present instance, a hooked rod 18, fixed to the diaphragm, engages with a bridle 19, 95 having its end fastened to the armature in such manner that the stresses imposed upon the opposite ends of the armature by threads 16^a become balanced, to provide against one 100 end of the armature snapping over against its corresponding pole piece due to unequal stress distribution.

The initial flexure of diaphragm 16 as above described, also permits the efficient use of a large diaphragm, which diaphragm 105 may yet be very thin, and therefore flexible and sensitive, and of light weight. If a thin and flexible diaphragm be employed under ordinary circumstances, since the diaphragm yields readily, a large air gap might 110 have to be employed to prevent the diaphragm or its armature from snapping over or sticking to the pole pieces, and furthermore the flexibility of the diaphragm might 115 bring about the result that the magnetic attraction of the armature would affect only a relatively small part of the area of the diaphragm. But if the diaphragm be initially flexed, a very small air gap nevertheless 120 may be employed as above described, and the tension upon the material of the diaphragm insures that the magnetic forces will be transmitted over the major portion of its area. The diaphragm may be constructed of very thin steel, and the invention 125 also makes possible the use of readily stretchable materials such as paper, or hide, since the tension on the diaphragm makes it taut to a much greater extent than would be possible merely by magnetic pull. Thus 130

the higher tones (those above two thousand cycles) are not lost, which otherwise might occur if a very thin flexible diaphragm were used.

5. As is illustrated in Fig. 4, the magnet structure and diaphragm may be mounted within a suitable casing 20, the edges of the diaphragm being held between the adjacent wall of the casing and a ring 21 overlying 10 the same. The diaphragm 16 is also preferably placed in communication with the outer air either directly or through a horn or the like 22, having an opening substantially equal in area to the area of the diaphragm; thus resonance chambers are avoided, permitting the energy of the diaphragm 15 to be transferred to the surrounding air without the generation of resonance tones.

While a specific embodiment has been disclosed, it will be obvious that many changes may be made therein without departing from the principle of the invention, as defined in the appended claims.

I claim:

25. 1. A telephone receiver comprising a magnetic circuit of predetermined magneto motive force, a branch magnetic circuit in parallel therewith, a sound reproducing diaphragm, said circuits having pole pieces 30 adapted to influence said diaphragm, and a coil inductively related to said branch circuit, said branch circuit being separated by portions of high reluctance from the first magnetic circuit.

35. 2. A telephone receiver comprising a magnetic circuit of predetermined magneto motive force, a branch magnetic circuit in parallel therewith, a sound reproducing diaphragm, said circuits having pole pieces 40 adapted to influence said diaphragm, and a coil inductively related to said branch circuit, said branch circuit having portions of high reluctance at its opposite ends separating the same from the first-mentioned 45 circuit.

3. A telephone receiver comprising a sound reproducing diaphragm, a magnetic circuit, and a branch circuit in parallel therewith, said circuits having pole pieces 50 to influence said diaphragm, the branch circuit including portions of high reluctance separating it from the first mentioned circuit.

4. A telephone receiver comprising a sound reproducing diaphragm, a magnetic circuit, a branch circuit in parallel therewith, said circuits having pole pieces to influence said diaphragm, the branch circuit having portions of high reluctance separating it from the first mentioned circuit, and means for varying the effect of the branch circuit.

5. A telephone receiver comprising a magnetic circuit of predetermined magnetic motive force, a branch magnetic circuit in

parallel therewith, a sound reproducing diaphragm, said circuits having pole pieces adapted to influence said diaphragm, and a coil inductively related to said branch circuit, said first-mentioned circuit including a portion of relatively high reluctance in series with said branch circuit.

6. A telephone receiver comprising a magnetic circuit of predetermined magnetic motive force, a branch magnetic circuit in parallel therewith, a sound reproducing diaphragm, said circuits having pole pieces adapted to influence said diaphragm, and a coil inductively related to said branch circuit, said first-mentioned circuit having an air gap therein in series with said branch circuit.

7. A telephone receiver comprising a magnetic circuit of predetermined magnetic motive force, a branch magnetic circuit in parallel therewith, a sound reproducing diaphragm, said circuits having pole pieces adapted to influence said diaphragm, a coil inductively related to branch circuit, said first-mentioned circuit including a portion of relatively high reluctance in series with said branch circuit, and the branch circuit also having a portion of relatively high reluctance therein.

8. A telephone receiver comprising a magnetic circuit, and a branch circuit in parallel therewith, a sound reproducing diaphragm, said circuits having pole pieces to influence said diaphragm, and said first circuit having a portion of relatively high reluctance in series with the branch circuit.

9. A telephone receiver comprising a flexible diaphragm, pole pieces adapted to influence the same, and balancing means for exerting a force additional to the magnetic pull from the pole pieces tending to flex said diaphragm in the direction of the magnetic pull, said means exerting a force on the diaphragm greater than the maximum magnetic pull.

10. A telephone receiver comprising a flexible diaphragm, an armature connected thereto, pole pieces adapted to influence said armature, and balancing means to exert a force additional to the magnetic pull from the pole pieces tending to urge said armature in the direction of the magnetic pull, said means exerting a force on the diaphragm greater than the maximum magnetic pull.

11. A telephone receiver comprising a flexible diaphragm, an armature connected thereto, said diaphragm and armature being substantially equal in weight, and pole pieces adapted to influence said armature.

12. A telephone receiver comprising a flexible diaphragm, an armature connected thereto, said diaphragm and armature being substantially equal in weight, pole pieces adapted to influence said armature, and

110

115

120

125

130

means additional to the magnetic pull from the pole pieces for urging said armature in the direction of the magnetic pull to flex the diaphragm, said means exerting a force 5 larger than the maximum magnetic pull.

13. A telephone receiver comprising a flexible diaphragm, an armature connected thereto, pole pieces adapted to influence said armature, said armature having dimensions 10 so related to the magnetic field passing through the pole pieces as to produce substantially a maximum ratio of magnetic force to the weight of the armature.

14. A telephone receiver comprising a magnetic circuit of predetermined magneto motive force, a branch magnetic circuit in parallel therewith, said first-mentioned circuit having pole pieces adapted to influence a diaphragm, and an armature adjacent 20 said pole pieces, said branch circuit also having a pole disposed adjacent said armature and being separated at a point remote from said armature by a portion of high reluctance from the first circuit.

15. A telephone receiver comprising a magnetic circuit of predetermined magneto motive force, a branch magnetic circuit in parallel therewith, said first-mentioned circuit having pole pieces adapted to influence 30 a diaphragm, and an armature adjacent said pole pieces, said branch circuit having a pole in proximity to the armature, and being separated at a point remote from said armature by a portion of high reluctance 35 from the first-mentioned circuit, said pole pieces being small in cross section when compared to the remaining portions of the magnetic circuit associated therewith.

16. A telephone receiver comprising a magnetic circuit of substantially constant magneto motive force, a variable magnetic circuit in parallel therewith, said circuits 40

having pole pieces in common, and an armature adjacent said pole pieces, said pole pieces being spaced a distance not greater 45 than the order of three times the length of the armature air gap.

17. A telephone receiver comprising a source of magneto motive force, pole pieces of opposite polarity in adjacent positions, 50 an armature in proximity to said pole pieces, and an additional pole piece having one extremity located between the first-named pole pieces, and having its opposite extremity separated from one of said first-named pole pieces by a gap of relatively 55 high reluctance.

18. A telephone receiver comprising a source of magneto motive force, pole pieces of opposite polarity in adjacent positions, 60 an armature in proximity to said pole pieces, an additional pole piece having one end adjacent the first-named pole pieces, and having its opposite end separated from one of said pole pieces by a gap of relatively 65 high reluctance, and a closed conductor of relatively low resistance mounted on one of said pole pieces.

19. A telephone receiver comprising a magnetic circuit with operating poles, an 70 armature spaced therefrom, members urging the armature towards the poles but not in contact therewith, a diaphragm, a connection between the armature and the diaphragm adjusted to strongly tense the diaphragm and to pull the armature away 75 from the pole pieces, the tension in said connection being greater than the maximum magnetic pull on the armature.

In testimony that I claim the foregoing, 80 I have hereunto set my hand this 18th day of April, 1922.

LESTER L. JONES.
